United States Patent Office

Des. 181,244
Patented Oct. 15, 1957

181,244

WRITING INSTRUMENT OR THE LIKE

Clarence Zierhut, Los Angeles, Calif., assignor to Paper Mate Manufacturing Company, Culver City, Calif., a corporation of Delaware

Application November 13, 1956, Serial No. 43,720

Term of patent 14 years

(Cl. D74—17)

Fig. 1.   Fig. 2.   Fig. 3.

Fig. 1 is a front elevational view of a writing instrument showing my new design;

Fig. 2 is a side elevational view thereof;

Fig. 3 is a rear elevational view thereof; and

Fig. 4 is a top plan view thereof.

I claim:

The ornamental design for a writing instrument or the like, substantially as shown.
